UNITED STATES PATENT OFFICE.

MILTON SHERIDAN SHARP, OF HECKMONDWIKE, ENGLAND.

PROCESS OF FIXING THE FINISH ON COTTON PIECE GOODS.

SPECIFICATION forming part of Letters Patent No. 645,237, dated March 18, 1900.

Application filed August 26, 1898. Serial No. 689,597. (No specimens.)

To all whom it may concern:

Be it known that I, MILTON SHERIDAN SHARP, a subject of the Queen of Great Britain and Ireland, residing at Heckmondwike, in the county of York, England, have invented certain new and useful Improvements in Processes of Fixing the Finish on Cotton Piece Goods; and I do hereby declare the following to be a clear and exact description of the invention, such as will enable others skilled in the art to which it appertains to make and use the same.

The object of my invention is to finish cotton piece goods of the class called "Italians," such as are generally used for the lining of coats, in such a manner that the luster is more uniformly brilliant, having a silk-like appearance, and of a more permanent character than is the case with fabrics treated in the ordinary manner.

In the accompanying drawings, Figure 1 represents a side elevation of an ordinary stretching-machine suitable for stretching and damping the fabric. Fig. 2 is a plan of the same; Fig. 3, a detached detailed plan of a portion of the stretching-machine chain; Fig. 4, an end view of the same; Fig. 5, an elevation of an ordinary steam-heated hydraulic press, partly in section; and Fig. 6, an end view of the same.

In carrying out my invention the cotton piece goods are in the first instance finished as hitherto in any of the well-known ways of pressing, calendering, or embossing; but, as is well known, the finish so produced is not permanent, as the luster is damaged or destroyed when the fabric is by any means damped or in the "making up" of garments.

In order that the luster produced by any of the ordinary methods may be permanently fixed and of uniform brilliancy, free from spots throughout the entire length and breadth of the fabric, I damp the fabric uniformly, preferably by subjecting the fabric to steam at a low temperature—that is to say, by what is known as "wet" or "saturated" steam. This I find can be conveniently done during the time the fabric is passing through a stretching-machine of the ordinary construction, such as is used in one of the stages of finishing.

The stretching-machine is provided with

sprocket-wheels A A and B B. The wheels A A are mounted on shaft C, and B B on shaft D, to which rotary motion is imparted in any convenient manner. The sprocket-wheels A A are placed upon the shaft C, nearer to each other than are sprocket-wheels B B, and upon the wheels are mounted chains E and E'. Each link of the chains is provided with a series of pins F, upon which the fabric is hooked and passed slowly through the machine in the direction of the arrow, and by the sprocket-wheels B B being farther apart than are the wheels A A the fabric on passing through the machine is stretched. The stretched fabric is stripped from the pins F by the ordinary rotating rollers G G and passed over roller H, driven by a belt passing over pulleys J J. The chains E and E' pass through box-guides K K', which are also farther apart at the end next wheels B B than at the end next wheels A A.

In the stretching-machine are placed a series of shallow troughs L between the side frames M of the machine and the under side of the chains E and E' with the fabric thereon, or the trough may extend the length of the chain box-guides K K'. In either case I place a series of steam-jet pipes P, regulated by taps, on the opening of which wet or saturated steam is injected into the trough or troughs. The steam on rising and escaping from the trough or troughs passes through the fabric above same, thereby thoroughly and uniformly damping the same. The damped fabric, finished by any of the ordinary processes hitherto in use, is then folded along with press-papers of the kind hitherto in use, but damped, the finished or lustrous side of the fabric in each fold being in contact with one side of a damped press-paper. The folded fabric and damped press-papers are then placed between the plates R R of an ordinary hydraulic press, which are heated by steam passing through the jointed pipes S into the hollow plates R and escaping through the jointed pipes S', as usual. The folded fabric and damped press-papers placed between the heated hollow plates R R are subjected to great pressure applied to the ram W in the ordinary manner, heat being applied to the said plates by the regulation of the supply of steam as may be required to obtain the amount

of luster or brilliancy in the fixed finish. After subjecting the folded fabric and damp press-papers to heat and pressure for a period they are taken out of the press, the 5 damped press-papers removed, and the cotton fabric wrapped in a thick fold of dry cotton cloth, preferably in a condition it is in as it leaves the loom, known as "in the gray." The two are then placed into the steam-heated 10 hydraulic press and subjected to heat and pressure for a period varying according to the thickness or weight and quality of the fabric on which the luster is to be permanently fixed.

What I claim as my invention is—
15 The process of fixing the luster on cotton piece goods consisting in damping and folding the fabric along with damped press-papers, and subjecting them to pressure, then wrapping the fabric in a fold of dry cotton cloth 20 and subjecting them to heat and pressure in the manner substantially as herein described.

In witness whereof I have hereunto set my hand in the presence of two witnesses.

MILTON SHERIDAN SHARP.
